UNITED STATES PATENT OFFICE.

CHARLES LEFEBURE, OF CHILlicothe, OHIO.

HEATING-STOVE.

1,186,999.

Specification of Letters Patent. Patented June 13, 1916.

Application filed June 25, 1915. Serial No. 36,259.

To all whom it may concern:

Be it known that I, CHARLES LEFEBURE, a citizen of the United States, and resident of Chillicothe, in the county of Ross and State of Ohio, have invented certain new and useful Improvements in Heating-Stoves; and I do hereby declare the following to be a full, clear, and exact description of the invention, such as will enable others skilled in the art to which it appertains to make and use the same.

My invention relates to an improved heating stove, and more particularly to that type of stove in which the heating of a room or a food receptacle is accomplished by heating a current of air and then directing said current of air to the points to be heated.

It is one of the objects of my invention to provide a stove of the above-mentioned character in which the fire-box is made of refractory material to conserve a portion of the heat generated therein.

Another object of my invention resides in the provision of a refractory element immediately adjacent and above the fire-box to conserve a portion of the heat emanating from the latter.

A still further object of my invention resides in the provision of a deflector above the fire-box and refractory element and in spaced relation with respect to the walls of the stove, to deflect and diffuse the heat within the interior of the stove to maintain a more nearly uniform temperature than would otherwise be possible.

Still another object of my invention resides in the provision, on the top of the stove, of a depressed receptacle support not in communication with the interior of the stove, but the walls of which form a portion of the top of the stove and are heated directly from the fire-box, and also heat is supplied directly to a receptacle placed thereon by a current of air coming from a pipe entering near the bottom of the stove and having its outlet in said receptacle support.

Other objects of my invention than those specifically hereinabove set forth will be apparent from the following specification in which I will describe my invention more in detail with particular reference to the form illustrated on the accompanying drawing, and which is illustrative of a certain embodiment thereof, which I have found in practice to give good results.

In the drawings: The figure represents a central section elevation through one form of heating stove constructed according to the present invention.

In the form shown 1 designates a cylindrical stove body open at the lower end and beneath which is located a fire-box 2 of refractory material. Resting on the upper edge of the fire-box 2 and having a downwardly directed deflecting flange is the annular member 3 to which the stove body 1 is secured in any suitable manner.

Beneath the fire-box 2 is an ash-pit 4 and upon this ash-pit the fire-box 2 is supported and retained against displacement by an annular rib 5. The top of the ash-pit 4 is provided with a grate aperture 6 of circular formation and in this aperture is mounted a grate 7 which may be given lateral oscillatory movement by means of a hand lever 8 connected therewith. At the front the ash-pit 4 is provided with an opening closed by a door 9 through which the ashes may be removed.

The entire structure is supported on suitable legs 10.

Within the stove body 1 and above the fire-box 2 is mounted a channel ring 11. In this ring and supported thereby are bricks 12 of refractory material. The upper ends of these bricks rest and are retained in place by a ring 13 similar to the ring 11. At one point in the refractory element thus formed is located a door opening provided with a door 14 through which the supply of fuel to the fire-box may be replenished.

Above the refractory element and secured to the stove body 1 internally thereof by lugs 16 and rivets 17 and in spaced relation with respect to the internal walls of the stove body, is a centrally apertured inverted conical shaped deflector 18.

The upper end of the stove body 1 is closed by a head or top 19 in which is located a depressed receptacle support 20, and in this top 19 is also located a smoke-pipe or chimney 21. The depressed receptacle support does not open into the interior of the stove and is covered at the top by a perforate closure 22.

In near proximity to the fire-box and just above the combustion zone, the stove body 1 is apertured. An air-pipe 22' leading from near the floor enters this aperture and extends inwardly and upwardly in the stove body 1 and through a central aperture in the

deflector 18 and has its outlet end in the lowest point of the receptacle support 20. It will thus be evident that a current of air rising in the pipe 22', due to the heat in the fire-box 2, will be heated and distributed at the outlet end of said pipe 22' and may be used for heating a room and also a receptacle. Also it is to be noticed that an annular deflector 23 is provided around the top of the 10 stove body 1 and serves to deflect the heat radiating from the heated walls of the stove body 1 which is also used for heating the room in which the stove is located.

While I have hereinabove described a certain embodiment of my invention, yet it is to be understood that variations and modifications may be made therein without departing from the spirit and scope of the invention, as set forth in the accompanying claims.

20 I claim:

1. The combination in a heating stove including a fire-box and ash-pit, of a refractory element immediately adjacent said fire-box to conserve the heat issuing therefrom, 25 an inverted conical shaped deflector above said refractory element to diffuse the heat within said stove, a depressed receptacle support at the top of said stove and cut-off from communication with the interior thereof, and an air tube entering said stove in proximity to said fire-box and extending upwardly through said stove and communicating with said receptacle support whereby heated air will be directed against a receptacle placed on said support, substantially as described.

2. The combination in a heating stove including a fire-box and ash-pit, of a refractory element immediately adjacent said fire-box to conserve heat issuing therefrom, an

inverted centrally apertured conical shaped deflector above said refractory element and in spaced relation with respect to the walls of said stove to diffuse the heat within the latter, a depressed receptacle support at the top of said stove and cut-off from communication with the interior thereof, and an air tube entering said fire-box in close proximity thereto and extending upwardly and inwardly through said stove and through the central aperture in said deflector and having its outlet end in communication with said receptacle support whereby heated air will be directed against a receptacle placed on said support, substantially as described. 55

3. The combination in a stove including a fire-box and ash-pit, of a ring of refractory material immediately adjacent and above said fire-box to conserve heat issuing therefrom, and a deflector above said ring to diffuse heat issuing from said fire-box and ring, substantially as described.

4. In a stove including an ash-pit, a fire-box of refractory material and a ring of refractory material immediately adjacent said fire-box, both the fire-box and ring serving to conserve the heat of combustion in the fire-box; and a deflector above said fire-box and ring to diffuse the heat issuing therefrom within the interior of the stove, substantially as described. 70

In testimony whereof I have signed this specification in the presence of two subscribing witnesses.

CHARLES X. LEFEBURE.
